UNITED STATES PATENT OFFICE.

VICTOR B. HUMPHREYS, OF LOS ANGELES, CALIFORNIA.

COLLAPSIBLE CAMP CUPBOARD.

Application filed June 9, 1924. Serial No. 718,805.

To all whom it may concern:

Be it known that I, VICTOR B. HUMPHREYS, a citizen of the United States, residing at Los Angeles, in the county of Los Angeles and State of California, have invented new and useful Improvements in Collapsible Camp Cupboards, of which the following is a specification.

This invention is a collapsible camp cupboard and consists of the novel features herein shown, described and claimed.

An object is to make a cupboard which is easily set up or extended and which is easily collapsed or knocked down.

Other objects and advantages will appear from the drawings and specification.

The drawings illustrate the collapsible camp cupboard embodying the principles of the invention.

Figure 1 is a perspective of the collapsible camp cupboard set up or extended for use.

Fig. 2 is a perspective of the cupboard partly set up or partly collapsed.

Fig. 3 is a perspective of the cupboard completely collapsed.

Fig. 4 is a fragmentary sectional detail on the line 4—4 of Fig. 1 and looking downwardly as indicated by the arrows.

Fig. 5 is an enlarged fragmentary perspective detail of one of the latches for holding the cupboard unfolded.

The details of construction and operation shown in the drawings are as follows:

The back 1 is the full size of the cupboard. The abutments 2 and 3 are placed against the side edges of the back 1 and rigidly secured in place by nails 4 and 5. The abutments 2 and 3 are just wide enough to extend forwardly from the back 1 a little more than the thickness of the shelf boards and the abutments extend the full length of the back. The shelf boards 6, 7, 8, 9 and 10 each have metal binding strips 11 and 12 secured along their end faces and the bound boards fit loosely between the abutments 2 and 3 in front of the back 1 and are secured pivotally in place by screws 13 and 14 inserted through the abutments and through the binding strips 11 and 12 into the shelf boards so that the shelf boards will swing freely from horizontal position downwardly to vertical position. The shelf boards are spaced apart far enough so that when they swing downwardly as in Fig. 2 they will all lie flat against the back 1.

Washers 15 and 16 are placed against the front ends of the binding strips 11 and 12 and connecting bars 17 and 18 are placed against the washers. Pivot screws 19 and 20 are inserted through the connecting bars 17 and 18 through the washers 15 and 16 and through the binding strips 11 and 12 into the boards, said connecting bars 17 and 18 serving to pivotally connect the five shelves at their front sides. The connecting strips 17 and 18 have notches 21 formed from their rear edges to receive the pivot screws 13 and 14 when the shelves swing downwardly. The lower ends of the connecting bars 17 and 18 extend below the shelf 10 to form latch members 22 and 23.

The side boards 24 and 25 are connected to the abutments 2 and 3 by hinges 26 and 27 and are adapted to swing inwardly to cover the folded shelves as shown in Fig. 3, and are adapted to swing outwardly into alignment with the abutments 2 and 3 as shown in Figs. 1 and 2. Latch members 28 and 29 are secured against the inner faces of the side boards 24 and 25 near their lower ends and have teeth 30 and 31 bent inwardly away from the boards and then backwardly to the boards, and teeth 32 extending upwardly and forming slots 33 between the teeth and the boards behind the teeth so that when the side boards 24 and 25 are swung open and the shelves 6, 7, 8, 9 and 10 are swung upwardly to horizontal positions, the latch members 22 and 23 will snap over the teeth 32 into the slots 33 and rest upon the teeth 30 and 31 and hold the shelves in their elevated horizontal positions.

Recesses 34 and 35 are formed in the upper face of the shelf 10 in position to receive the teeth 29 and 30 when the side boards are folded.

Thus I have produced a very simple collapsible camp cupboard which when collapsed is only three boards thick and which is set up to produce a substantial cupboard with only three movements; one movement to swing the side 24 open, the second movement to swing the side 25 open, and the third movement to swing the shelves 6, 7, 8, 9 and 10 upwardly to horizontal positions, and the cupboard is as easily collapsed or folded. Any one of the shelves may be engaged to raise the shelves slightly above normal to bring the latches 22 and 23 out of engagement with the hooks; then the sides 24

2
and 25 are spread apart beyond normal to allow the shelves to swing downwardly to folded positions.

Various changes may be made without departing from the spirit of the invention as claimed.

I claim:

1. A collapsible cupboard comprising a back, abutments extending from the edges 10 of the back, a series of shelves pivotally mounted between the abutments, bars pivotally connecting the forward parts of the shelves together independent of side boards, side boards hinged to the abutments and 15 adapted to unfold so the shelves will swing upwardly between the side boards, and means for latching the shelves to the side boards to hold the shelves in unfolded positions and to hold the side boards from 20 swinging outwardly.
2. A collapsible cupboard comprising a back, abutments extending forwardly from the side edges of the back, shelves hingedly mounted with their rear portions between 25 the abutments, connecting bars pivotally attached to the swinging portions of the shelves to operate the shelves simultaneously and independent of the side boards, side

boards hinged to the abutments and adapted to swing outwardly into lines with the abutments so that the shelves will swing downwardly and fold against the back, the connecting bars being adapted to remain within the back and side boards, and the side boards will swing inwardly and cover the folded 35 shelves and connecting bars, and means for holding the shelves and side boards unfolded.

3. In a collapsible cupboard, a back, side boards connected to the back and adapted to swing and fold inwardly and to swing outwardly at right angles to the back, shelves mounted to swing downwardly against the back and to simultaneously swing upward to horizontal positions between the folding side boards and independent of said side 45 boards, and means for holding the shelves in their horizontal positions comprising bars pivotally connected to the outer ends of the shelves and prong shaped latches attached to the side boards and adapted to support the 50 connecting bars in elevated positions and to secure the connecting bars to the side boards adjacent them.

In testimony whereof I have signed my name to this specification.

V. B. HUMPHREYS.
